UNITED STATES PATENT OFFICE

OTTO MANTIUS, OF NEW YORK, N. Y.

METHOD OF WASHING PULP

Application filed April 6, 1928. Serial No. 267,977.

This invention is a method of washing pulp and is more particularly directed to the removal of chemicals from pulp produced by the soda, sulphate or sulphite processes well known to the art.

After pulp is discharge from the digester, it is the practice to remove therefrom the soda, sulphate or sulphite which it contains in order to recover such chemical and to prepare the pulp for bleaching.

This washing has been generally carried on heretofore by passing the pulp from the digester to large wash tanks or diffusers which, in many instances are arranged in batteries 15 through which the pulp to be washed is successively fed, while fresh water is passed through the tanks to wash out the chemical.

This well known washing arrangement requires large amounts of fresh hot water for 20 carrying on the operation and is thus expensive. Furthermore, when very large quantities of water are used to wash out the chemicals, these chemicals form a solution with the water and in order to recover them 25 costly processes of concentration and recovery are required.

The purpose of the present invention is to provide a method whereby increased efficiency may be obtained in the washing of 30 pulp through the use of a novel method of manipulation of the material which makes it possible to accomplish the result by the use of relatively small quantities of water, as compared to prior known processes.

35 I am able to accomplish this result by entirely departing from the wash tank batteries and diffusers of prior practice and in lieu thereof subjecting the pulp to successive washing operations with intermediate 40 applications of pressure.

In practice, the pulp, as discharged from the digester, usually contains about 90 parts of water to 10 parts of pulp, and in this water the chemical, which it is desired to remove, is contained in solution. The initial

step in this method consists in subjecting the pulp to pressure to at once squeeze out most of the water contained therein in order that the greater portion of the chemical contained therein may be immediately 50 removed from the pulp. Thereafter I add water to the pulp and then subject the pulp to a further pressing operation for freeing the pulp of the water last added together with such additional chemical as may have 55 become admixed therewith. These operations are repeated and before each pressing operation I add to the pulp additional water to further dilute the chemical contained therein, so that when the pressing operations 60 take place, the water which is removed during such operations carries off with it a part of the chemical in solution. For example, if the pulp is compressed as it comes from the digester, a large portion of the 65 water content will be removed and the pulp will be partially dehydrated through such compression. If the pulp is thereupon thoroughly admixed with more water, a further portion of the chemical which remains in 70 the pulp will be diluted by the water.

At the conclusion of this washing operation, which consists in thoroughly admixing the partially dried pulp with further water, the pulp is again compressed to again partially dehydrate it by squeezing out the water previously added. This water carries off with it a further portion of the chemical. If these operations are repeated several times, an unusually efficient removal of the 80 chemical from the pulp results and this efficiency is materially increased if, before each pressing operation, the washing operation is accompanied by a shredding and intimate admixture of the pulp with the diluting water to which I have referred.

Thus, the preferred practical manner of carrying out the present invention consists in pressing the pulp to free it of a portion of its water-chemical solution, thereafter 85

shredding the pulp and thoroughly admixing it with further diluting water, and thereafter repeating these steps in the sequence stated any desired number of times found requisite to impart to the pulp the desired freedom of chemical content.

Furthermore, in practice, I find it entirely satisfactory and in fact highly desirable to take the washwater resulting from one washing stage and use it in the next preceding washing stage, preferably using fresh water for the last washing stage. I am thus required to feed fresh water to only the last washing stage and to supply water to the preceding washing stages by what may be termed countercurrent washing. By employing this type of washing, the amount of water ultimately used is but a small fraction of that used in prior processes, with resulting manifest advantages among which may be mentioned economy in hot water and also the economy of steam required for the recovery of the chemicals through concentration for further use.

I have found it highly desirable in practice to obtain the most intimate contact between the water and the pulp fibres during the washing operation, in order that maximum dilution may result during each washing operation. I therefore preferably subject the pulp during, and as a part of the washing operation, to a shredding and kneading action in the presence of the wash water, so that the pulp is thoroughly washed and maximum dilution results.

Further important practical features will be apparent from the following detailed description and claims when read in conjunction with the accompanying drawings.

The accompanying drawings illustrate one practical form of apparatus for carrying out the method of this application, but inasmuch as other forms of apparatus may be used to accomplish this result, the showing made in the drawings is to be understood as illustrative, only, and not as defining the limits of the invention.

Figure 1 is a diagrammatic view showing apparatus for carrying out the process of this invention.

Figure 2 is an enlarged detail elevation showing apparatus forming a part of the structure illustrated in Figure 1, and functioning to press the pulp in order to squeeze the water therefrom.

Figure 3 is a vertical longitudinal section through shredder and washing apparatus shown diagrammatically in Figure 1. This section is taken on the line 3—3 of Figure 4.

Figure 4 is a plan view of the structure shown in Figure 3.

Figure 5 is a side elevation of the same structure showing the manner in which the moving parts are driven.

Figure 6 is a section showing apparatus

for removing a portion of the water squeezed out from the material.

Figure 7 is a section on the line 7—7 of Figure 6 showing certain parts in elevation.

The whole apparatus is preferably, though not essentially, mounted within a suitable casing designated in Fig. 1 of the drawings by the reference character 1. This casing may be of any suitable form or construction and may, in practice, be the room of a building.

By reference to Fig. 1, it will be noted that there are a number of conveyors mounted within this casing, and in this figure, I have shown five of them. They are respectively designated 2, 3, 4, 5 and 6. These conveyors are mounted one above the other and in such relation that they are adapted to cooperate with one another. Thus, the lower reach 7 of the conveyor 2 is positioned to cooperate with the upper reach 8 of the conveyor 3. The lower reach 9 of the conveyor 3 cooperates with the upper reach 10 of the conveyor 4, the lower reach 11 of the conveyor 4 cooperates with the upper reach 12 of the conveyor 5, while the lower reach 13 of the conveyor 5 cooperates with the upper reach 14 of the conveyor 6.

It will be noted, moreover, that the conveyors are positioned in staggered relation, so that each projects a distance beyond the other in order that pulp placed on the conveyor 3 to the left of the conveyor 2 in Fig. 1 may be fed by the conveyor 3 between the reaches 7 and 8 to be fed after passing between said conveyors to a shredder and washer 15 positioned beyond the discharge end of the conveyor 3. This shredder and washer is positioned above the projecting portion of the conveyor 4, so that after the material is passed through the shredder and washer 15, it is fed to the conveyor 4 to be carried thereby between reaches 9 and 10 of the conveyors 3 and 4 and discharged into a second shredder and washer 16 from which it is in turn discharged on to the conveyor 5 to be carried thereby between the reaches 11 and 12 of the conveyors 4 and 5 and thereupon discharged into a third shredder and washer 17, from which it is thereafter discharged on to the lowermost conveyor 6 to be carried thereby between the reaches 13 and 14 and delivered down an incline 18 through a hole 18' into a suitable trough by which the material is conveyed away.

All of the conveyors 2—6 are of the same construction and I find it highly practical to employ slat conveyors, such as shown in Figure 2. Here each conveyor is illustrated as embodying metal slats 20 extending transversely of the direction of travel of the conveyor and for the full width of the machine. These slats are positioned edge to edge and are mounted on sprocket chains 21 by which they are supported and moved. The sprocket

chains operate about suitable spacing and driving sprockets 22 as shown and these sprockets are all driven at the same speed so that the conveyors will all travel at uniform speeds. The cooperating reaches of the several conveyors have associated with them pressure rolls. That is to say, above the lower reach 7 of the uppermost conveyor 2 are positioned a plurality of pressure rolls 23, 24 and 25 and cooperating with the upper reach 8 of the conveyor 3 and positioned directly below the rolls 23, 24 and 25 are cooperating rolls 23a, 24a and 25a. These rolls are positioned to engage with the backs of the slats 20 of the conveyors with which they cooperate and, as shown in Fig. 2, said rolls are positioned at progressively decreasing distances apart. Thus, the rolls 23 and 23a are positioned slightly further apart than the rolls 24 and 24a which in turn are positioned slightly further apart than the rolls 25 and 25a, so that those portions of the conveyors which travel between said rolls form a converging mouth in the direction of travel of the conveyors. The rolls 23, 24 and 25 and the cooperating rolls 23a, 24a and 25a are mounted in suitable bearings, so as to be held firmly in position although the bearings may be spring pressed or weighted so that if the conveyors meet with abnormal resistance due, e. g., to unyielding foreign matter carried into the converging mouth by the material acted upon, the rolls may slightly retract or be moved apart sufficiently to permit the material to pass through without damaging the apparatus.

Under normal conditions, however, the pressure rolls are mounted so that the cooperating reaches of the conveyors will not move apart, but will subject the material fed between said conveyors to a constantly increasing pressure as it is carried along by and with the conveyors. Thus, if material is fed on to the upper reach of the conveyor 3 down a feed table 26 and is carried by the conveyor into cooperative relation with the conveyor 2, it will necessarily follow that such material will be carried through the converging pressure mouth formed in the manner described whereby the material will be compressed in a substantially solid cake and during this operation, a large percentage of the water contained in the material will be squeezed out therefrom.

The rollers which I have described are those cooperating with the lower reach of the conveyor 2 and the upper reach of the conveyor 3, but the three sets of rolls associated with the other cooperating reaches of the several conveyors are formed and mounted in the same manner and function for the same purpose as already explained. I refer in this connection to rolls 33, 34 and 35 and their cooperating rolls 33a, 34a, and 35a, as well as the rolls 43, 44, and 45 and their cooperating

rolls 43a, 44a and 45a and also the rolls 53, 54 and 55 and their cooperating rolls 53a, 54a and 55a. As a matter of fact, the several sets of rolls are pressure rolls and their purpose is to provide sufficient pressure to squeeze out a large proportion of the material presented thereto and to form the material into a substantially solid cake.

During the pressing operations, considerable water is freed from the material and this water is caught by troughs 30, 40, 50 and 60 which are positioned directly beneath the upper reaches of each of the conveyors 3, 4, 5 and 6.

The shredders and washers of which three are shown in Figure 1 are illustrated more in detail in Figs. 3 to 5 inclusive. All of the washers are of the same construction. Each embodies a suitable tank 61 in which is mounted a plurality of drums 62, 63 and 64, three of which are shown, although a greater or lesser number may be provided. The drums are mounted to rotate on parallel axes in suitable bearings and the bottom of the tank is in the form of arcuate shaped troughs 62a, 63a and 64a. These troughs are curved on radii of which the axes of the respective drums are the centers. The periphery of each drum has formed thereon diamond shaped studs 65 and similarly shaped studs are formed on the inner faces of the troughs in such manner that the studs of the respective parts are substantially complementary to one another, but are so placed as to permit rotation of the drums in the troughs and with respect to one another.

The arrangement may be fully appreciated from the showing in Figs. 3 and 4 and it may be stated that there is one less annular row of studs on the trough 62a than on the cooperating drum 62. The same relation exists as to the drum 64 and the trough 64a, whereas there is one less row of studs on the drum 63 than on the cooperating trough 63a. This produces a staggered relation of the parts which permits of rotation. Because of the interfitting of the studs, however, the material passed through the washer is subjected to a shredding and at the same time a kneading action, while the rotation of the drums serves to simultaneously feed the material fed into the tank from the feed table 66 longitudinally through the tank and thoroughly shred and comminute it.

The material is freed from the last drum by a comb 67 having a serrated edge complementary to the studs of said drum and this comb interfits with the studs and combs the fibres free from the drum whereby they are caused to fall on to a discharge plate 68 which delivers them to the next conveyor.

The shredding and kneading drums may be operated by any suitable drive mechanism, but for the purpose of illustration, I have shown the drums as having drive pulleys 62b,

63b and 64b with which a belt 69 is associated. This belt is passed over the several pulleys referred to and around directional and tensioning pulleys 70 and embraces a pulley 71 mounted on the shaft which drives the conveyor 3 so that the several drums are driven from the shaft 72 which drives the conveyor 3, whereby the several drums are driven with the said conveyor.

10 By reference to Fig. 1, it will be noted that the shredder and washer 17 is supplied with fresh water through a pipe 73. The shredder and washer 16 is supplied from water in the trough 60 through a pipe 74, while the shredder and washer 15 is supplied by water from the tank 50 through a pipe 75. A pipe 76 delivers water from the trough 40 to the outlet pipe 84 which leads to suitable recovery apparatus. Suitable pumping means, shown as 20 centrifugal pumps 100, is provided for causing the passage of water through these pipes.

The apparatus which I have thus far described is employed in operating upon pulp in the following manner. The pulp is taken 25 as it comes from the digester in a loose semi-solid condition and containing generally about 90 parts of water-chemical solution and 10 parts of pulp, and this semi-solid mass is fed into the apparatus down the table 26 30 on to the conveyor 3.

The wet semi-solid mass moves along with the conveyor 3 until it is carried thereby into cooperation with the conveyor 2, whereupon both conveyors cooperate to compress the 35 mass and feed it through the tapering mouth between the pressure rolls 23, 23a, 24, 24a, 25 and 25a. During its passage between said rolls, it is subjected to increasing pressures and a large percentage of the water therein 40 is squeezed out so that the material will be delivered from the last cooperating rolls 25 and 25a in the form of a relatively solid cake or web. The water which is freed in the manner described carries with it an appreciable part of the chemicals which enter into 45 solution with the water. The water freed from the under side of the material passes through the cracks between the conveyor slats and falls into the trough 30. The water freed 50 from the upper face of the material is squeezed through the cracks between the slats of the upper conveyor on to the upper surface of the lower reach of such conveyor. A part of this water overflows through a bypass pipe 77 into the trough 30, while the remainder of such water is picked up by the apparatus shown in Figs. 6 and 7 and delivered to the tank 30 through a pipe 78.

The apparatus shown in Figures 6 and 7 60 embodies a perforated metal cylinder 79 mounted to rotate freely on hollow trunnions 80. The cylinder 79 is covered with absorbent material 81, such as soft felt which as it rolls over the conveyor acts as a blotter to 65 suck up the water. A hard surface roll 82

bears against the felt covering 81 at the top thereof and causes the water to be squeezed out through perforations in the circumference of the cylinder. This water falls into the interior of the cylinder and is caught in a 70 basin 81 which communicates with a hollow trunnion 80. The pipe 78 is connected with a hollow trunnion, so that the water thus gathered is conveyed through the pipe 78 to the trough 30. This apparatus has been found 75 in practice to give unusually satisfactory results, particularly in dealing with hot liquids where a pump would not operate satisfactorily.

Apparatus such as shown in Figures 6 and 80 7 is associated with each gang of pressure rolls and an overflow pipe 77 also cooperates therewith.

The solid cake or ribbon resulting from the first pressing operation is delivered from the conveyor 3 by way of table 66 to the first shredder and washer 15. This shredder and washer thoroughly shreds the cake or comminutes it while washwater is fed to the shredder and washer through a pipe 75. 90

The shredding and washing thus takes place in the presence of further water in order that the chemical within the material may be further diluted. The material is delivered from the shredder and washer 15 in efficiently 95 divided form and in a wet semi-solid condition to the upper reach of the conveyor 10, which serves to carry the material into cooperation with the lower reach of the conveyor 3 and these conveyors collectively pass the 100 material through the second pressing operation to again form the material into a cake and simultaneously squeeze out the water-chemical solution into the trough 40. After leaving the second gang of pressure rolls, the 105 material is delivered to a second shredder and washer 16 supplied with water through the pipe 74 and wherein a second shredding and washing operation with further dilution takes place. The material is delivered from the 110 second shredder and washer on to the upper reach 12 of the conveyor 5 to be carried thereby between the third gang of pressure rolls, which deliver a third cake or web to a third shredder and washer 17 and simultaneously 115 deliver the products of the further dilution to the tank 50.

The shredding and washing operations described are repeated in the apparatus 17 supplied with water through the pipe 13 and the finely divided pulp is thereupon delivered to the conveyor 6 to be passed therewith through the fourth and last pressing operation, the aqueous product of which is received in the trough 60 while the resulting cake or web is 120 fed down the incline table 81 out of the machine.

Particular attention is called to the fact that prior to each compressing operation, a diluent is added and each time the material is 125 130

subsequently compressed, this diluent is squeezed out, carrying therewith a portion of the chemical previously contained in the pulp. In other words, each time the material is washed and thereafter compressed, it is freed of a further portion of the chemical so that by successive washings and pressings, the material is finally freed of substantially all its chemical content. In practice, I find it thoroughly practical to feed fresh water through the pipe 73 to the last washer 17, while the washers 16 and 15 are supplied from the troughs 60 and 50, respectively. This constitutes in effect a countercurrent washing with the last washing stage utilizing fresh water. This is a highly efficient manner of treating the material since a relatively small portion of fresh water is required with consequently less water flowing from the trough 30 through the pipe 84 for treatment to recover the chemicals.

Particular stress is placed on the fact that the operation of treating the pulp is continuous, the pulp being in the state of continuous movement from the time it enters until it leaves the machine. Thus, I am able to obtain with a minimum supply of water a thorough washing with maximum speed and output. The pulp which is operated upon by the apparatus shown and described is of a very slippery nature which renders its compression by rolls alone difficult. It is for this reason that the continuous cooperating conveyors are employed in conjunction with the rolls to efficiently feed the pulp through the pressure zones.

Each roll assembly has been illustrated as embodying three sets of cooperating rolls, but a greater or lesser number may be used. Moreover, if desired, I may employ pressure roll assemblies of the character described and claimed in my Patent No. 1,764,456 of June 17, 1930, "Fiber board machine" but such apparatus is not essential for the carrying out of the present method, it being particularly desirable here to produce a flushing or circulation of the water through the material so that it will entrain the chemicals and carry them off in solution.

It will be apparent from the foregoing detailed description of the method and one form of apparatus used in performing the same that this method of manipulating the pulp to free it from its chemical content is a marked departure from the prior practice of employing open wash tanks or diffusers with many times the amount of water utilized in performing the present process. Moreover, by employing mechanical washers and shredders, a thorough washing results and the diluent is brought into most intimate contact with all the fibres of the pulp, a circumstance which is absent in practically all prior practice. In other words, the present invention provides for the most intimate commingling

of the diluent with all parts of the pulp in order that a maximum dilution may result. It may be further noted that the detrimental channeling so common in open wash tank operation cannot occur in the method of this invention.

The foregoing detailed description sets forth the invention in its preferred practical form. The apparatus shown as illustrative has been found to give thoroughly satisfactory results, but inasmuch as other and different apparatus may be employed for the same purpose, the method is not restricted to the use of that shown in the drawings. On the contrary, the method of this invention is to be understood as fully commensurate with the appended claims.

Having thus fully described the invention, what I claim as new and desire to secure by Letters Patent is:

1. The herein described method which consists in subjecting pulp, in a loose watery condition and containing a chemical, to pressure to squeeze out an appreciable portion of the water and chemical contained therein, thereafter kneading and shredding the pulp in a bath of diluent to thoroughly and intimately commingle the fibers of the pulp with the diluent to dissolve the chemical still contained in the pulp, then again subjecting the pulp to pressure to substantially free it from such diluent whereby further chemical which has entered into solution with the diluent is removed from the pulp.

2. The herein described method which consists in subjecting pulp, in a loose watery condition and containing a chemical, to pressure to squeeze out an appreciable portion of the water and chemical contained therein, thereafter kneading the pulp in a bath of diluent to thoroughly and intimately commingle the fibers of the pulp with the diluent to dissolve the chemical still contained in the pulp, then again subjecting the pulp to pressure to substantially free it from such diluent whereby further chemical which has entered into solution with the diluent is removed from the pulp.

3. The herein described method which consists in subjecting pulp, in a loose watery condition and containing a chemical, to pressure to squeeze out an appreciable portion of the water and chemical contained therein, thereafter shredding the pulp in a bath of diluent to thoroughly and intimately commingle the fibers of the pulp with the diluent to dissolve the chemical still contained in the pulp, then again subjecting the pulp to pressure to substantially free it from such diluent whereby further chemical which has entered into solution with the diluent is removed from the pulp.

4. The herein described method which consists in compressing the pulp to squeeze out a portion of the chemical therefrom and si-

multaneously forming the pulp into a solid web, feeding the web into a bath of diluent, shredding the web and kneading the shredded fibers while in the bath to thoroughly and 5 intimately admix the diluent with such fibers of the pulp, then again compressing the pulp to form it again into a solid web and to free it from the diluent and a further portion of the chemical which entered into solution 10 with the diluent during the shredding and kneading operations.

In testimony whereof I have signed the foregoing specification:

OTTO MANTIUS.
